United States Patent Office

Des. 213,510
Patented Mar. 11, 1969

213,510

MODEL AIRCRAFT

John P. Kukon, Trenton, N.J., John R. Fitzpatrick, Levittown, Pa., and Juergen K. Bock, Toms River, N.J., assignors to Aereon Corporation, Trenton, N.J., a corporation of Pennsylvania

Filed Apr. 29, 1968, Ser. No. 11,692

Term of patent 14 years

U.S. Cl. D34—15
Int. Cl. D21—02

FIG. 1.

FIG. 2.

FIG. 4.

FIG. 3.

FIG. 5.

FIG. 6.

FIGURE 1 is a plan view of a model aircraft showing our new design,

FIGURE 2 is an elevational view taken from the right side thereof,

FIGURE 3 is a bottom plan view thereof,

FIGURE 4 is an elevational view taken from the right side of the view in FIGURE 3,

FIGURE 5 is a front elevational view taken from the bottom of FIGURE 1, and

FIGURE 6 is a rear elevational view taken from the top of FIGURE 1.

We claim:

The ornamental design for a model aircraft, as shown.
